MINING MACHINE HEAD

Charles E. Compton, Shinnston, W. Va.

Application February 3, 1951, Serial No. 209,261

6 Claims. (Cl. 262—9)

1

This invention relates to a mining machine head. It relates particularly to a mining machine head of the type comprising a rotatable and advanceable cutter element having a material passage therethrough extending generally parallel to the axis of rotation and having periphery cutting means mounted thereon at the forward end thereof and an inner element substantially coaxial with the cutter element and at least partially disposed therewithin and facing in the same direction, the inner element having inner cutting means mounted thereon at the forward end thereof.

Mining machine heads of the type above referred to are disclosed in my Patent No. 2,562,841. Such heads have proven eminently satisfactory in the mining of coal. I obtain therewith unprecedented tonnage per man hour without undesirably breaking up the coal. The heads are of relatively simple construction and can be fabricated at low cost. Their upkeep cost is likewise low.

Coal in different localities varies in characteristics including hardness and structure. The heads disclosed in my said application are perfectly satisfactory for bituminous coal mined from the Pittsburgh seam in West Virginia. However, coal in other localities having different characteristics presents somewhat different problems. Relatively hard coal is more highly resistant to fracture by the breaker of my mining machine head. I have found that for some operations the inner element should be hollow. When the inner element is made hollow it provides a material passage therewithin entering the same at the forward end thereof into which passes some of the material of the body of material being operated upon. That material is preferably discharged from within the inner element into the material passage through the outer element. This may be provided for by making an opening in the wall of the inner element intersecting or communicating with the material passage therewithin so that the material received within the inner element passes rearwardly therein for a distance and then passes outwardly through the wall of the inner element into the material passage through the outer element. The inner element desirably has a wall inclined to its axis to insure breaking off of material entering the inner element forming part of the body of material being operated upon and projecting such material laterally out of the material passage in the inner element into the material passage in the outer element.

2

The inner element is preferably a cutter element having inner cutting means mounted thereon at the forward end thereof. It is also preferably a breaker small enough at its forward end to enter the opening formed by the inner cutting means but wider than that opening at its rearward end to break or fracture the material outside it. The breaker is preferably of a width approximating that of the opening formed by the inner cutting means at a zone not substantially in advance of the periphery cutting means. The breaker desirably has outwardly projecting rib means forming a generally spiral conveyor extending rearwardly and circumferentially. That conveyor is of relatively coarse pitch with adjacent convolutions spaced apart to provide passage space therebetween of materially greater cross-sectional area than the rib means, and the conveyor is desirably pitched and the passage spaced proportioned to the size of the inner cutting means so that the passage space accommodates and the conveyor conveys rearwardly substantially all of the cuttings formed by the inner cutting means which enter the passage space and the conveyor engages and propels rearwardly lumps of the material.

Also, for operating upon material of different characteristics the forward end of the inner element should be in different axial relationships to the forward end of the outer element. I have devised a construction of universal applicability in respect of the relationship between the forward ends of the inner and outer elements; I provide connecting means connecting the inner element with the outer element cooperable with the elements when they are in different axial relationships to each other whereby the forward end of the inner element may be adjustably positioned relatively to the forward end of the outer element. Such construction is of great utility whether the inner element is a solid breaker as in my said patent or a hollow cutter element or a hollow breaker. In my presently preferred construction the inner element is a hollow breaker connected with the outer element by connecting means of the type above referred to.

I find it generally preferable to make the outer element in the form of a cylinder open at both ends. I also prefer to employ a rotatable and advanceable shaft which carries the inner and outer elements. Desirably the inner element telescopes either within or outside of the shaft, which is preferably hollow. The connecting means may be in the form of a bolt passing through the inner element and the shaft. To

provide for connecting the inner element with the shaft in different axial relationships thereto either the inner element or the shaft, or both, may be provided with a series of bolt receiving holes; adjustment is provided for by aligning desired holes in the inner element and the shaft and bolting the inner element to the shaft therethrough.

I desirably employ a spiral conveyor disposed about the shaft and mounted thereon for rotating and advancing movement with the shaft and adapted to convey rearwardly about the shaft material entering the forward end of the conveyor. The outer element is preferably mounted upon the spiral conveyor for rotating and advancing movement with the shaft and spiral conveyor. Normally the forward end of the inner element and the forward end of the outer element are in approximately the same transverse plane but through the above mentioned connection the inner element may be moved either forwardly or rearwardly relatively to the outer element so that the forward end of the inner element may project forwardly of the forward end of the outer element or the forward end of the inner element may be disposed rearwardly of the forward end of the outer element. When the inner element is a breaker it should, as above mentioned, be of a width approximating that of the opening formed by the inner cutting means at a zone not substantially in advance of the periphery cutting means. This enables the breaker to act on and break up the material surrounding the breaker and disposed generally within the outer element which has been partially severed from the mass of material being operated upon by the periphery cutting means mounted on the forward end of the outer element.

Other details, objects and advantages of the invention will become apparent as the following description of a present preferred embodiment thereof proceeds.

In the accompanying drawings I have shown a present preferred embodiment of the invention, in which

Figure 1 is a perspective view with portions cut away of a mining machine head;

Figure 2 is an end view of the mining machine head shown in Figure 1 as viewed from the front end thereof or generally from the left-hand end viewing Figure 1;

Figure 3 is a perspective view of the inner element of the mining machine head shown in Figures 1 and 2; and

Figure 4 is a central vertical longitudinal cross-sectional view through the mining machine head.

Referring now more particularly to the drawings, the mining machine head shown therein comprises a shaft 2, a spiral conveyor 3 mounted on and disposed about the shaft 2, an outer cylindrical cutter element 4 mounted on and carried by the spiral conveyor 3 and an inner hollow breaker and cutter element 5 carried by the forward end of the shaft 2. The shaft 2 is preferably hollow as shown and is of a size to enable it to carry the load imposed in operation. Normally the diameter of the shaft 2 may range from 6" to 18" or more depending on the size of the mining machine head. The spiral conveyor 3 may be an appropriately shaped metal plate welded to the outside of the shaft 2 so that when the shaft 2 is rotated and advanced the conveyor 3 conveys rearwardly along and outside the shaft 2 material entering the conveyor at the front end thereof. The front end of the conveyor termi-

nates within the outer element or cylinder 4, entering that cylinder far enough to enable the cylinder to be welded thereto throughout a sufficient length of the conveyor to form a strong unitary head comprising the shaft 2, the spiral conveyor 3 and the cylinder 4. The cylinder is preferably of such diameter that it fits snugly about the front end of the spiral conveyor 3, enabling it to be welded thereto. The cylinder 4 forms a rotatable and advanceable outer cutter element having a material passage therethrough extending generally parallel to the axis of rotation. It has periphery cutting means mounted thereon at the forward end thereof. The periphery cutting means mounted on the forward end of the cylinder 4 are cutters 6, 7 and 8, the cutters 6 projecting somewhat outwardly from the outer surface of the cylinder, the cutters 7 being disposed generally in the plane of the material of the cylinder and the cutters 8 projecting somewhat inwardly from the inner surface of the cylinder. The cylinder 4 has spirally arranged rods 9 and 10 welded to its outer and inner surfaces respectively to convey rearwardly any fine material formed by the action of the cutters 6, 7 and 8 and lying generally in the path of the cylinder as it rotates and advances into the material being operated upon. The cutter element 4 is adapted to cut a generally cylindrical kerf in a body of material upon rotation and advancement thereof.

The inner element 5 is shown in perspective in Figure 3. It comprises a hollow cylindrical shank 11 and a head 12 of somewhat greater diameter than the shank 11 at its forward end tapering down to approximately the diameter of the shank 11 at its rearward end where it is welded to the shank as indicated at 25 to form a unitary structure. The shank 11 is of such diameter as to have a snug sliding fit within the hollow shaft 2. The shank 11 may be internally reinforced by welding or otherwise fastening therein adjacent the right-hand extremity thereof viewing Figures 3 and 4 a collar 13. Bolt receiving holes 14, 15 and 16 are formed through the shank 11 and the collar 13 therewithin to permit a fastening bolt to pass completely through the shank. The hollow shaft 2 may be externally reinforced by welding thereto reinforcing means 17 and a bolt receiving hole 18 is formed through the shaft and the reinforcing means 17 to receive a fastening bolt 19 which also passes through a selected one of the holes 14, 15 and 16 in the shank of the inner element to adjustably fasten the inner element to the shaft and hence to the outer element 4 inasmuch as the outer element is rigid with respect to the shaft. A nut 20 is applied to the bolt 19 to maintain the inner element firmly fastened to the shaft. Thus the bolt constitutes connecting means connecting the inner element with the outer element cooperable with the elements when they are in different axial relationships to each other whereby the forward end of the inner element may be adjustably positioned relatively to the forward end of the outer element.

The forward end of the head 12 of the inner element 5 is in the form of a hollow cylinder having inner cutting means in the form of cutters 21, 22 and 23 mounted thereon at the forward extremity thereof. The cutters 21 project somewhat outwardly from the outer surface of the head 12, the cutters 22 are disposed generally in the plane of the material of the head 12 and the cutters 23 project somewhat inwardly from the inner surface of the head. The head 12 has

5

spirally arranged ribs 24 welded to its outer surface. The ribs 24 are shown as forming a generally spiral conveyor on the outer surface of the head 12 of the inner element 5 extending rearwardly and circumferentially and also increasing in radial height from front to rear along the head 12. Thus the inner element 5 constitutes a hollow breaker coaxial with the outer element 4 and connected therewith and having inner cutting means mounted on the forward end thereof, the hollow breaker being small enough at its forward end to enter the opening formed by the inner cutting means but being wider than that opening at its rearward end by reason of the gradually increasing height of the spiral ribs 24. Preferably the hollow breaker at a zone not substantially in advance of the periphery cutting means 6, 7 and 8 is of a width approximating that of the opening formed by the inner cutting means 21, 22 and 23 so that the inner element acts as a breaker as above mentioned.

The inner element 5 has a material passage therewithin entering the same at the forward end thereof. The passage is indicated by reference numeral 26. The passage 26 communicates with the material passage through the cylinder 4 rearwardly of the forward end of the head 12. An opening 27 is formed through the wall of the head 12 to form a passage communicating between the passage 26 and the material passage inside the cylinder 4. The head 12 also has a wall 28 consisting of a heavy plate welded in place as shown and inclined to the axis of the head to insure breaking off of material entering the passage 26 forming part of the larger body of material being mined and projecting such material laterally out of the inner element 5 through the opening 27 into the material passage in the cylinder 4. The radial depth of the opening 27 is, as shown in Figure 4, somewhat greater than the radius of the forward end of the head 12 of the inner element 5. The wall 28 is shown as being both radially and circumferentially inclined to insure breaking off of any material within the inner element 5 which may tend to adhere to the mass of material being operated on and forceably ejecting the broken off material out of the inner element as the mining machine head advances and rotates.

The rods 10 welded to the inner surface of the cylinder 4 are relatively small and of generally round cross-section adjacent the forward end of the cylinder. These small round rods extend rearwardly within the cylinder from the forward end thereof generally in a relatively tight spiral to a point near the center of the opening 27 or near the center of the plate 28 at which point at least some of the small round rods change in shape to generally half-round or similar cross section and begin to increase in height radially of the cylinder as they extend rearwardly as clearly shown in Figure 4. The tapered rearward portions of the rods 10 extend rearwardly generally in a spiral of coarser pitch than the smaller round forward portions thereof, the rods at their rearward ends being of substantially the same pitch as the spiral conveyor 3 and one thereof forming substantially a forward extension of the spiral conveyor 3.

The tapered portions of the rods 10 attain at their rearward ends a radial height somewhat greater than the radial distance between the inside surface of the cylinder 4 and the inside of the kerf cut into the material being operated upon by the cutters 6, 7 and 8. Thus if a portion

6

of the material has not broken off from the main body of material by the time it strikes the enlarged rearward portions of the rods 10 that portion will be engaged and pressed inwardly thereby to cause the same to break off from the main body of material before entering the spiral conveyor 3.

Similarly, the tapered spiral ribs 24 attain at their rearward ends a radial height materially greater than the radial distance between the outside surface of the forward end of the head 12 and the outside of the kerf cut into the material being operated upon by the cutters 21, 22 and 23 so that the ribs 24 act to expand and crack the material about the inner element 5. At the same time, however, the radial distance between the radially outward surfaces of the rearward ends of the ribs 24 and the radially inward surfaces of the radially opposed rods 10 is slightly less than the radial distance between the outside surface of the kerf cut by the cutters 21, 22 and 23 and the inside surface of the kerf cut by the cutters 6, 7 and 8 so as to prevent jamming of the material between the rearward ends of the ribs 24 and the radially opposed portions of the rods 10.

While I have shown and described a present preferred embodiment of the invention it is to be distinctly understood that the invention is not limited thereto but may be otherwise variously embodied within the scope of the following claims.

I claim:

1. A mining machine head comprising a rotatable and advanceable cutter element having a material passage therethrough and an annular rotatable and advanceable element substantially coaxial with and at least partially within said cutter element and facing in the same direction, said annular element having cutting means at the forward end thereof, said annular element having outwardly projecting means rearwardly of the forward end thereof providing passage space therebetween of materially greater cross-sectional area than said outwardly projecting means and said annular element being small enough at its forward end to enter the opening formed by said cutting means but being wider than that opening rearwardly of its forward end and at the portion of said projecting means of greatest transverse dimension whereby to constitute a breaker, said annular element having passage means therethrough to permit material therewithin to pass generally transversely out of said annular element into the space within said cutter element.

2. A mining machine head comprising a rotatable and advanceable cutter element having a material passage therethrough and an annular rotatable and advanceable element substantially coaxial with and at least partially within said cutter element and facing in the same direction, said annular element having cutter means at the forward end thereof, said annular element having outwardly projecting rib means rearwardly of the forward end thereof forming a generally spiral conveyor of relatively coarse pitch extending rearwardly and circumferentially, adjacent convolutions of the conveyor being spaced apart to provide passage space therebetween of materially greater cross-sectional area than the rib means, and said annular element being small enough at its forward end to enter the opening formed by said cutting means but being wider than that opening rearwardly of its forward end and at the portion of the rib means of greatest

transverse dimension whereby to constitute a breaker, said annular element having passage means therethrough to permit material therewithin to pass generally transversely out of said annular element into the space within said cutter element.

3. A mining machine head comprising a rotatable and advanceable cutter element having a material passage therethrough, an annular rotatable and advanceable element substantially coaxial with and at least partially within said cutter element and facing in the same direction, said annular element having cutting means at the forward end thereof, said annular element having outwardly projecting means rearwardly of the forward end thereof providing passage space therebetween of materially greater cross-sectional area than said outwardly projecting means and said annular element being small enough at its forward end to enter the opening formed by said cutting means but being wider than that opening rearwardly of its forward end and at the portion of said projecting means of greatest transverse dimension whereby to constitute a breaker, said annular element having passage means therethrough to permit material therewithin to pass generally transversely out of said annular element into the space within said cutter element, and connecting means connecting said annular element to said cutter element cooperable with said elements when they are in different relationships to each other in the direction generally parallel to the axis of rotation whereby the forward end of said annular element may be adjustably positioned relatively to the forward end of said cutter element.

4. A mining machine head comprising a rotatable and advanceable shaft, a cutter element of greater diameter than the shaft and having a material passage therethrough connected with the shaft to rotate and advance therewith and an annular element substantially coaxial with and at least partially within said cutter element and facing in the same direction, said annular element being connected with the shaft to rotate and advance therewith, said annular element having cutting means at the forward end thereof, said annular element having outwardly projecting means rearwardly of the forward end thereof providing passage space therebetween of materially greater cross-sectional area than said outwardly projecting means and said annular element being small enough at its forward end to enter the opening formed by said cutting means but being wider than that opening rearwardly of its forward end and at the portion of said projecting means of greatest transverse dimension whereby to constitute a breaker, said annular element having passage means therethrough to permit material therewithin to pass generally transversely out of said annular element into the space within said cutter element.

5. A mining machine head comprising a rotatable and advanceable shaft, a conveyor screw mounted on the shaft to convey rearwardly of the shaft upon rotation thereof material entering the screw, a cutter element carried by the screw so that the shaft, screw and cutter element form a rotatable and advanceable unit, the cutter element having a material passage therethrough communicating with the conveyor screw, and an

annular element substantially coaxial with and at least partially within said cutter element and facing in the same direction, said annular element being connected with the shaft to rotate and advance therewith, said annular element having cutting means at the forward end thereof, said annular element having outwardly projecting means rearwardly of the forward end thereof providing passage space therebetween of materially greater cross-sectional area than said outwardly projecting means and said annular element being small enough at its forward end to enter the opening formed by said cutting means but being wider than that opening rearwardly of its forward end and at the portion of said projecting means of greatest transverse dimension whereby to constitute a breaker, said annular element having passage means therethrough to permit material therewithin to pass generally transversely out of said annular element into the space within said cutter element whence the material is delivered rearwardly by said conveyor screw.

6. A mining machine head comprising a rotatable and advanceable cutter element having a material passage therethrough, an annular rotatable and advanceable element substantially coaxial with and at least partially within said cutter element and facing in the same direction, said annular element having cutting means at the forward end thereof, said annular element having outwardly projecting means rearwardly of the forward end thereof providing passage space therebetween of materially greater cross-sectional area than said outwardly projecting means and said annular element being small enough at its forward end to enter the opening formed by said cutting means but being wider than that opening rearwardly of its forward end and at the portion of said projecting means of greatest transverse dimension whereby to constitute a breaker, said annular element having passage means therethrough to permit material therewithin to pass generally transversely out of said annular element into the space within said cutter element, and means disposed generally within said annular element and extending generally transversely thereof to break off material withing said annular element whereafter said material passes through said passage means.
